BOAT MOORING AND LIFTING MECHANISM

Anthony C. Lange, Milwaukee, Wis.

Application May 14, 1948, Serial No. 26,949

4 Claims. (Cl. 61—65)

1

This invention appertains to boat mooring devices and more particularly to a novel device for lifting and holding a boat, when not in use, above storm wave crest.

With small boats, it is customary either to drag the same ashore or up on a dock, to anchor the same beyond the shoreline, or to tie the boat to a dock. All of these methods are open to objection. For instance, when a small boat is tied to a dock, there is always the danger of the boat banging up against the dock, particularly in stormy weather.

It is, therefore, one of the primary objects of my invention to provide a portable device which can be submerged close to the shore line or alongside of a dock over which the boat can be floated and thereafter, quickly and conveniently raised out of the water, safe above wave action.

Another salient object of my invention is to provide a boat mooring device embodying a base having skids or runners for engaging the water bottom, upon which is rockably mounted a cradle for the boat, with novel means for raising and lowering the cradle and the boat out of and into the water.

A further object of my invention is to provide novel means for adjusting the angle of the base of the boat mooring device relative to the cradle, so that the base will conform to the slope of the bottom and thereby permit the cradle to be maintained parallel with the normal water level at all times.

With these and other objects in view, the invention consists in the novel construction and arrangement of parts, as will be hereinafter more specifically described and claimed, and illustrated in the accompanying drawings, in which drawings:

Figure 1 is a side elevational view of my novel boat mooring device showing the same in operative position alongside of a dock, the cradle of the mooring device being shown in its raised position holding a boat out of the water in full lines and in its lowered position in dotted lines, parts of the figure being shown broken away and in section to illustrate certain structural detail.

Figure 2 is a substantially horizontal sectional view taken on the line 2—2 of Figure 1, looking in the direction of the arrows illustrating the construction of the base.

Figure 3 is a fragmentary, transverse, sectional view through the mooring device taken on the line 3—3 of Figure 1 looking in the direction of the arrows.

Figure 4 is a view similar to Figure 3 but taken

2

on the line 4—4 of Figure 1 looking in the direction of the arrows.

Figure 5 is a transverse, sectional view through the base taken on the line 5—5 of Figure 1 looking in the direction of the arrows.

Figure 6 is a fragmentary, detail, longitudinal, sectional view illustrating a slightly modified form of mechanism for raising and lowering the cradle.

Referring to the drawings in detail, wherein similar reference characters designate corresponding parts throughout the several views, the letter M generally indicates my novel boat mooring device, and the same includes a base 10, a cradle 11 for a boat B and the operating mechanism 12 for raising and lowering the cradle on the base.

The boat B forms no part of the present invention and can be of any preferred character or type.

The base 10 includes a pair of spaced parallel longitudinally extending runners or skids 13 and 14. These runners or skids form means for permitting the boat mooring device to be pulled into and out of the water similar to a sleigh. The opposite ends of the runners or skids 13 and 14 can be slightly upturned, as at 15, if such should be desired. Any preferred materials can be utilized for the runners or skids, and as shown, the same are made from angle bars. A front arched transversely extending bracebar 16 is utilized for rigidly connecting the runners together adjacent to their forward ends. A similar rear bracebar 17 is also utilized, and this bracebar 17 is connected to the runners by a series of telescoping legs 18, for a purpose which will be later set forth. The front and rear bracebars 16 and 17 are rigidly connected together by a centrally disposed longitudinally extending beam 19. In the present instance, this beam has been shown to be of tubular form and welded securely to the transverse bracebars. The beam 19 carries the cradle 11 and the raising and lowering mechanism 12, and it is desirable to maintain the longitudinal beam 19 parallel with the normal water level. The telescoping legs 18 can be adjusted so as to permit the runners 13 and 14 to conform to the angle or slope of the level or other water bottom. The front and rear bracebars 16 and 17 are rigidly connected together by a centrally disposed longitudinally extending beam 19.

In the present instance, this beam has been shown to be of tubular form and welded securely to the transverse bracebars. The beam 19 carries the cradle 11 and the raising and lowering mechanism 12, and it is desirable to maintain the longitudinal beam 19 parallel with the normal water level. The telescoping legs 18 can be adjusted so as to permit the runners 13 and 14 to conform to the angle or slope of the level or other water bottom. The section of the telescoping legs 18 are held in a preferred selected adjusted position by any preferred means such as bolts 20.

The cradle 11 for the boat includes front and rear spaced parallel cross arms 21 and 22. These cross arms extend transversely of the base and are rigidly connected by a centrally disposed lon-

gitudinally extending backbone or beam 23. The cross arms 21 and 22 can be formed from angle iron and the longitudinal connecting beam 23 is preferably formed from a pair of angle irons and a center strip with certain flanges 25 of the angle bars disposed in a horizontal plane to form a rest for the keel of the boat. Blocks 26 are rigidly secured to the cross arms 21 and 22, and these blocks have their upper faces shaped to conform to the general transverse contour of a boat bottom. The blocks have their inner ends spaced so as to permit the keel of a boat to ride between the same.

The cross arms and the longitudinal beam 23 forms a rigid top frame upon which the boat to be lifted rests. This top rigid frame is rockably connected to the base. The means employed for connecting the rigid top frame with the base includes a pair of spaced parallel front levers 27 and a pair of rear similar spaced parallel rear levers 28. The levers of each pair are rigidly connected together and braced in any preferred manner such as by the use of transversely extending spacer tubes 29. The levers 27 include telescoping sections 30 and 31, so that the levers can be extended or shortened, as desired. A bolt 32 is utilized for each pair of levers to hold the sections thereof in a selected adjusted position.

The extreme upper ends of the front pair of levers 27 are rockably connected to the front cross arm 21 and the central beam 23 by a cross pin 33. This pin rockably extends through the central beam 23 and through depending bearing lugs 34 formed on the cross arm 21. The rear pair of levers 28 are connected to the rear cross arm 22 in the same manner as the front pair of levers is connected to the front cross arm 21. Hence, a cross pivot bolt 35 is employed, and this bolt extends through the central beam 23 and through depending bearing lugs 36 carried by the cross arm 22. The bolt, of course, rockably extends through the upper sections 31 of the pair of rear levers 28. The lower ends of the front pair of levers 27 are rockably connected to the rear central beam 19 of the base frame by means of a cross pivot bolt 37, and this bolt extends through the extreme lower ends of the levers and through bearing brackets 38 welded to said base beam 19.

The rear pair of levers 28 is rockably connected to the base beam 19 adjacent to its rear end by cross pivot bolt 39, and this bolt extends through the extreme lower ends of the levers 28 and through the bearing brackets 40 welded or otherwise secured to the base 19.

Welded or otherwise secured to the inner faces of the lower sections 30 of the pair of levers 27 are cam shaped flanges 41. These flanges extend longitudinally of the levers and cooperate with the raising and lowering mechanism 12 which will now be described.

To bring about the raising and lowering of the cradle 11, I preferably employ a hydraulic lift mechanism which consists of a cylinder 42. This cylinder 42 extends longitudinally of the base frame and is securely fastened by means of cuffs 43 to the longitudinally extending base beam 19. Reciprocatively mounted in the cylinder 42 is a piston 44, and secured to the piston is a piston rod 45 which extends outwardly of the cylinder toward the front pair of levers 21. The piston is normally urged toward the rear of the cylinder by means of an expansion spring 46 coiled about the piston rod. This spring is confined between the piston 44 and one cylinder head.

Any well known type of hydraulic pump 47 is employed for forcing liquid under pressure to the rear end of the cylinder. The pump 47 is preferably made separate from the boat mooring device, so that the same can be placed on a dock or on shore as may be desired. As illustrated, the pump 47 includes a hand lever 48 for operating the same. Obviously, an electric motor can be employed for this purpose should such be desired. The outlet for the pump has communicating therewith a flexible tube 49, and the tube is connected with a rigid tube 50 arranged within the central beam 19 of the base. The tube 50 communicates with the rear end of the cylinder. Obviously, upon operation of the pump, fluid will be forced into the rear end of the cylinder moving the piston 44 forwardly. When pressure is relieved, the spring will move the piston back.

The extreme forward end of the piston rod 45 carries a crosshead 51, and this cross head carries a transversely extending shaft 52 on which is rotatably mounted a guide roller 53 which is adapted to move along the central brace beam 19. The shaft 52 also rotatably carries grooved end wheels 54 which engage the cam flanges 41 on the front pair of levers 27.

In use of my improved mooring device, the same is slid into the water at the desired location, such as alongside of a dock, and the pump 47 is placed on the dock. The legs 18 are adjusted so as to bring the beam 19 in a horizontal plane. The levers 27 and 28 are lengthened or shortened according to the depth of the water in which the base is submerged. Considering that the cradle 11 is in its lowered position, as shown in dotted lines in Figure 1, the cross arms 21 and 22 will be submerged below the water level and preferably just about the normal position of the bottom of the boat B to be accommodated. The boat is floated over the cradle on to the cross arms 21 and 22, and the boat user then steps out on the dock and operates the pump. Fluid under pressure will force the cross head 51 forwardly against the flanges 41, which will swing the levers 27 upwardly. The raising of the levers 27 will carry the levers 28, the beam 23 and the cross arms 21 and 22 therewith, and the boat will be elevated the desired distance above the water level.

When it is desired to lower the boat, the pump valve is operated to relieve the pressure in the cylinder, then the piston will be retracted by the spring 46. If the cradle is on dead center, a slightly rearward push can be given thereto by the operator.

A stop 55 can be carried by the extreme rear end of the central brace beam 19 for receiving the transverse brace for the rear pair of levers, when the cradle is in its lowered position.

In Figure 6, I have illustrated a slightly modified form of elevating mechanism for the cradle. In this form the rear pair of levers 28 are extended a considerable distance below the pivot pin 39 to form lift arms 56. A bell crank 57 is rockably mounted at its angle on a pivot pin 58 carried by the central beam 19 of the base. The short arm 59 of the bell crank is pivotally connected to the piston rod 60 of a piston 61. The piston is slidably mounted in the cylinder 62, which is in turn rigidly secured to the beam 19. An expansion spring 63 is coiled about the piston rod and is confined between a cylinder head and the piston. The rear end of the cylinder has communicating therewith a pipe 50 for the hydraulic fluid. The long arm 59 of the bell crank carries

rollers 64 for engaging the extended portions or lift arms 56 of the levers 28. When the piston 61 is moved forwardly, the bell crank is actuated so as to push down on the arms 56 and bring about the elevating of the cradle.

While I have illustrated the use of my invention as a boat mooring and lifting device, obviously, the invention can be used for any purpose where it is desired to elevate or lower heavy objects. Hence the runners 13 can be eliminated and wheels or casters substituted therefor.

Changes in details may be made without departing from the spirit or the scope of my invention, but what I claim as new is:

I claim:

1. A boat mooring device comprising a rigid base including runners, said base being adapted to be submerged in a body of water below the water level, said base also including a central beam, means connecting the forward end of the beam to the runners adjacent to their forward ends, means adjustably connecting the rear end of the beam to the runners adjacent to their rear ends to adjust the angle of the runners relative to the beam, a boat receiving cradle rockably mounted on the beam and movable to a lowered position below the water level and to a raised elevated position above the water level, and means for raising and lowering the cradle.

2. A boat mooring device comprising a base frame, a cradle for a boat including a rigid top frame having cross arms for the boat, front and rear levers rockably connecting the rigid frame to the base, said front lever having a longitudinally extending cam shaped bearing flange, a cylinder secured to the base frame, a piston in said cylinder, a piston rod connected to the piston extending forwardly of the cylinder, a cross head on the rod engaging said flange, means for forcing fluid under pressure to the rear end of the cylinder against the piston, and an expansion spring normally urging the piston toward the rear end of the cylinder.

3. A boat mooring device comprising a base frame including a pair of spaced parallel, longitudinally extending skids and a longitudinally extending central beam, a cradle for a boat including a top rigid frame having cross arms for receiving the boat, front and rear pairs of levers

rockably secured to the rigid frame at their upper ends and to the base frame at their lower ends, cam shaped guide flanges on the front pair of levers extending longitudinally thereof, a cylinder rigidly secured to the beam, a piston slidably mounted in the cylinder, a forwardly extending piston rod secured to the piston and extending outward of the cylinder, a cross head on the forward end of the piston rod having a guide roller engaging the central beam and operating rollers engaging the flanges on the front pair of levers, and means for operating the piston.

4. A boat mooring device comprising a base frame including a pair of spaced parallel longitudinally extending skids and a longitudinally extending central beam, a cradle for a boat including a top rigid frame having cross arms for receiving the boat, front and rear pairs of levers rockably secured to the rigid frame at their upper ends and to the base frame at their lower ends, cam shaped guide flanges on the front pair of levers extending longitudinally thereof, a cylinder rigidly secured to the beam, a piston slidably mounted in the cylinder, a forwardly extending piston rod secured to the piston and extending outward of the cylinder, a cross head on the forward end of the piston rod having a guide roller engaging the central beam and operating rollers engaging the flanges on the front pair of levers, and means for operating the piston, said levers including telescoping sections and means for securing the sections in a selected adjusted position.
